UNITED STATES PATENT OFFICE.

GUSTAV B. SCHNEIDER, OF CINCINNATI, OHIO.

STATION-INDICATOR FOR PASSENGER-CARS.

1,322,061.

Specification of Letters Patent. Patented Nov. 18, 1919.

Application filed February 19, 1919. Serial No. 277,975.

To all whom it may concern:

Be it known that I, GUSTAV B. SCHNEIDER, a citizen of the United States of America, and a resident of Cincinnati, in the county 5 of Hamilton and State of Ohio, have invented a new and useful Improvement in Station-Indicators for Passenger-Cars, of which the following is a specification.

My invention relates to station indicators, 10 which have a mechanism for moving the sign bearing devices, which are automatically and intermittently actuated at each station to exhibit the name thereof.

An object of my invention is a station 15 indicator in which the time of exposure of the name of each station will keep in accord with the time of the car's reaching that station, irrespective of the number or places of the stops or of the reversals, or of other 20 incidents of the travel of the car.

Another object of my invention is to improve and simplify the means for starting and stopping the motion of the mechanism.

These and other objects are attained by 25 the means described in the specification and illustrated in the accompanying drawings, in which:—

Figure 1, is a side elevation of the mechanism and a sectional view of the casing of 30 a station indicator embodying my invention.

Fig. 2, is a sectional view taken upon line 2—2 of Fig. 1.

Fig. 3, is a sectional view taken upon line 3—3 of Fig. 1.

Fig. 4, is a sectional view taken upon line 4—4 of Fig. 1.

Fig. 5, is a perspective view upon a reduced scale of my station indicator.

Fig. 6, is a plan view of a portion of the 40 trolley wires and the contact devices to be used with my invention.

Fig. 7, is a side elevation of the trolley 45 wires and contact points and of a trolley pole and contact device forming a detail of my invention.

Fig. 8, is a front elevation of the parts shown in Fig. 7.

Referring to the accompanying drawings, 50 in the preferred form of my invention the device which bears the names of the stations, is a web of paper A, which is rolled upon a roller a, passes thence in front of the display opening b, in the casing B, to a winding roll C, being held straight in front of the display opening by means of guide rolls a', a''. Roller C, has rotation imparted

to it in one direction, by a drive shaft D, which is alternately driven in opposite directions by electric motor E, which alternately receives a current from the contacts 60 f, f', which are carried by the trolley pole F. Contacts f, f', are adapted to engage contact plates G, G', which are carried alongside of the trolley wire F', by means of side wires g, g', which receive current 65 from the main wire F, by means of feed wires g², which are located at intervals along the trolley wire. Contact plates G, alternate with contact plates G' at successive stations. Plates G, G', are made angular in cross section, and contacts F, F', are each provided with two contacts, which are located upon the legs of the angle plate, in order to prevent the trolley wire, if it becomes broken, from sending a current to 75 the motor.

Wire f² conveys current from contact f, to the opposite side of the motor from the wire f³, which conveys current from the contact f', so that the current transmitted 80 to the motor from the contact plate G, rotates it in a direction opposite to that in which it is rotated by a current transmitted to it by the contact plate G', hence the drive shaft D is alternately rotated in opposite 85 directions by means of the pinions e', d, which are secured upon the shaft e of the motor and the drive shaft D, respectively.

The rotation of the driving shaft in opposite directions is a factor in securing a single 90 movement only of the indicator at each station irrespective of the length or of the number of the engagements of the contacts with each plate.

The means by which the opposite rotations of the drive shaft D are transmitted into a forward rotation of the paper roll, and the means for limiting the rotation of the paper roll, will now be described.

Shaft D, carries at its inner end a pinion d' which meshes with a gear wheel H, which is loosely mounted upon a shaft h. Upon each side of gear wheel H, ratchet wheels k, k' are loosely mounted upon the shaft h, the teeth of ratchet wheels k, k' point in opposite directions. Gear wheel H, carries dogs h', h², the former of which engages the teeth of ratchet k, and the latter of which engages the ratchet wheel k', so that the rotation of gear wheel H in one 110 direction, rotates ratchet wheel k, while leaving ratchet wheel k' stationary, and the

rotation of gear wheel H, in the opposite direction, rotates ratchet wheel k' in that direction and leaves ratchet wheel k stationary.

5 The rotations of ratchet wheels k , k' are alternately conveyed to paper roll C, by the following means:

10 Mounted upon shaft h , are two sleeves M and N, sleeve M has splined upon it one member m , of a clutch, the other member k^2 of which is secured to the ratchet wheel k . Sleeve N has splined upon it one member n' , of a clutch, the other member k^3 of which is secured to the ratchet wheel k' .

15 Members m and n' of the clutches are engaged by links P and R, the upper ends of which are pivoted to a stationary plate Q, and the lower ends of which are connected by a link S.

20 The means of throwing one clutch in as the other clutch is thrown out of engagement, is as follows:

25 Ratchet wheels k , k' , carry cams K, K', which are stationed in the path of cams p and r , which are secured upon the links P and R, respectively, so that when the cam r , contacts with cam K it carries member n' of the clutch away from its coöperating member, and through the medium of the

30 link S carries member m , of the opposite clutch into engagement with its coöperating member. Cams p , r , are positioned so that one clutch is thrown out before the other is thrown into gear. After passing the contact

35 plate at a station, since the action of the cam puts the indicator in position to be actuated only by a contact plate which is positioned upon the opposite side of the trolley wire, from the last contact plate, no further engagements of the contact with the last contact plate will affect a movement of the indicator. Thus the timing of the name of each station is kept in accord with the time of reaching said station.

45 I will now describe the means for connecting the sleeves M and N with the paper roll C. Sleeve M has secured upon it a gear wheel m' which engages a pinion e upon the shaft c' of the paper roll C. Sleeve N has secured upon it a gear wheel n , which meshes with an intermediate gear T, which is secured upon a stud shaft t upon which is secured a gear wheel T', which meshes with a gear wheel c^2 upon the shaft c' .

55 In describing the operation I will suppose that the car has passed the station at which is located a contact plate G, and that this would have caused the motor to have rotated the drive shaft D, in a direction to

60 impart motion to the ratchet wheel k , and to have caused the cam K to strike the cam p , and to open the clutch m and to close the clutch n' , thus putting the shaft c' of the paper roll into mesh with the stationary ratchet k' and the temporarily stationary

chain of gears, which connect ratchet k' with the shaft c' . When the contact f' strikes the contact plate g' , current will be imparted to the motor G to rotate it in an opposite direction to that in which it has just been rotated. This will likewise convey an opposite rotation to drive shaft D, which will, through the pinion d' gear wheel H, and dog h^2 , convey rotation to the ratchet wheel k' , which will convey rotation to the paper roll shaft c' , by means of clutch n' , sleeve N and gear wheels T, T' and c^2 . One rotation of the ratchet k' carries cam K into contact with cam r , and throws link R into a position which opens the clutch n' and closes the clutch m , thereby checking the rotation of the paper roll shaft c' by putting it into mesh with the temporarily stationary gear wheel m' , sleeve M, clutch m and ratchet k . This leaves the parts in position to be actuated by a current through the wire f^3 when the contact f' strikes the contact plate G' at the next station. Thus the web of paper is advanced at each station a sufficient distance to exhibit at the display 90 opening the name of the successive station.

Having described my invention, what I claim is:

1. In a station indicator the combination of a sign bearing device, an actuator for the sign bearing device, a drive shaft, means for imparting rotation in opposite directions at successive stations to the drive shaft and means for transmitting motion in a forward direction to the actuator from the successive rotations of the drive shaft.

2. In a station indicator the combination of a web bearing the names of successive stations, a winding roll for the web, a drive shaft, means for imparting rotation in opposite directions at successive stations to the drive shaft and means for transmitting a forward rotation to the roll from the successive rotations of the drive shaft.

3. In a station indicator the combination of a web bearing the names of successive stations, a winding roll for the web, a drive shaft, a means for imparting rotation in opposite directions at successive stations to the drive shaft, a gear wheel in mesh with the drive shaft, two trains of gears each in mesh with the winding roll, one of said train of gears being adapted to reverse the direction of the rotation imparted to it, a clutch between the gear wheel and each train of gears and means carried by the gear wheel adapted alternately to render the clutches inoperative.

4. In a station indicator for cars the combination of a sign bearing device, an actuator for the sign bearing device, a drive shaft, an electric motor, gears connecting the shaft of the electric motor and the drive shaft, two contact devices carried by the car, electrical conductors connecting the con-

tact devices to opposite sides of the motor, contact devices placed along the route of the vehicle those at alternate stations being placed in position to engage one of the 5 contact devices and those at the other stations being adapted to contact with the other contact devices, and means for transmitting

motion in a forward direction to the actuator from the successive rotations of the drive shaft.

In testimony whereof, I have hereunto subscribed my name this 18th day of February, 1919.

GUSTAV B. SCHNEIDER.
